UNITED STATES PATENT OFFICE.

LOUIS DUEMER, OF HAMILTON, OHIO.

FURNACE.

1,023,136.

Specification of Letters Patent. Patented Apr. 16, 1912.

Application filed July 20, 1910. Serial No. 572,795.

To all whom it may concern:

Be it known that I, LOUIS DUEMER, a citizen of the United States, residing at Hamilton, Butler county, Ohio, have invented certain new and useful Improvements in Furnaces, of which the following is a specification.

My invention pertains to heating furnaces and relates to improvements in the apparatus provided for moistening the heated air.

The invention will be readily understood from the following description of the drawing, which illustrates an exemplifying structure in which the invention is embodied.

15 Figure 1 is a view partly in elevation and partly in vertical section of a furnace embodying the invention: and Fig. 2 is a horizontal section on the line 2—2 of Fig. 1.

Reference character 1 designates the ash-box; 3, the fire-pot; and 4, the feed-throat. These, with the other general structural features of the furnace, may be of any usual or suitable type.

17 is an opening through the furnace casting conveniently placed adjacent to the fire-pot: 18, a water-pan disposed within the space between the fire-pot and the casing and accessible for filling and placing and removal through such opening, this pan having its inner wall lying up against the fire-pot: 19, a vertical partition dividing the pan into a main outer portion and a horizontally thin inner portion: 20, an aperture through the partition at the base of the main portion 30 of the pan, the thin inner portion of the pan being preferably somewhat deeper than the main portion: and 21, circumferential extensions of the thin inner portions of the water-pan, usually adapted, as shown, to 35 partially encircle the fire-pot.

In the ordinary water-pans employed in furnaces there is a tendency when water is liberally supplied for the water to boil over and, furthermore, the supply of water is 45 usually insufficient to provide the desired liberality of evaporation. My invention makes provision for improving on these conditions.

The object of the extensions 21 is to secure 50 a more extended contact of the water-pan with the fire-pot and at the same time permit the entire pan to be withdrawn through the opening in the casing, and for this same reason it is found advantageous to make one 55 of the extensions of superior length in case there be two of the extensions.

The thin inner compartment of the water-pan may be more or less filled with refractory granular material, fine pieces of brick, for instance, and the main portion of the 60 pan is to be filled with water. The water finds its way through small opening 20 to the granular material and, by capillary attraction, moistens the granular mass and the heat absorbed from the fire-pot rapidly 65 evaporates the water, continued supply being furnished from the main portion of the pan.

It is desirable that the inner compartment of the pan be deeper than the main compartment, as illustrated, in order that there may be water distributed throughout the length of the inner compartment where it can reach an extended surface of granular material and also in order that the main compartment 70 may be completely drained into the inner compartment. It is also highly desirable that the partition separating the two compartments of the pan be lower than the main walls of the pan in order that in case 75 boiling should take place in the inner compartment, the water may boil over into the cooler outer compartment. Water in the main portion of the pan is comparatively cool and without liability to boil over, and 80 at the same time the small body of water carried by the granular material is at high 85 heat and provides for rapid evaporation without danger of boiling over.

I claim:—

1. A furnace comprising, a fire-pot, a water-pan disposed against the fire-pot, said water-pan being open at the top, a partition forming the water-pan into a main outer compartment and a transversely thin inner 95 compartment, an aperture being provided in the base of the partition between the two compartments, and the top of the partition being lower than the main walls of the pan so that the water may boil over from one 100 compartment into the other without boiling over the sides of the pan, combined substantially as set forth.

2. A furnace comprising a fire-pot, a water-pan disposed against the fire-pot, said 105 pan comprising an inner portion lying against the fire-pot for a considerable part of the circumference thereof, and an outer part constituting a reservoir, the said inner part being deeper than the outer part, and a 110 partition between the parts, there being a small perforation at the bottom of the par-

tition leading from the outer to the inner part, the said inner part being open at the top.

3. A furnace comprising, a fire-pot, a water-pan disposed against the fire-pot, said water-pan being open at the top, and a partition forming the water-pan into a main outer compartment and a transversely thin inner compartment, an aperture being provided in the base of the partition between the two compartments, the inner compartment having a side extension against the fire-pot and beyond the width of the main compartment, combined substantially as set forth.

4. A water pan for furnaces, open at the top and divided by a partition into a main outer compartment and a relatively narrow

inner compartment, the said inner compartment being shaped to correspond to the wall 20 of the furnace and provided with side extensions resting against the wall of the furnace, the inner compartment being of greater 25 depth than the outer compartment, the partition having an opening in its base permitting communication between the two compartments and said partition terminating short of the upper edge of the pan to permit the water to boil over from one compartment into the other without boiling over the sides 30 of the pan.

LOUIS DUEMER.
